Patented Nov. 25, 1913.

UNITED STATES PATENT OFFICE.

CHARLES A. CARSCADIN AND GEORGE A. WOODMAN, OF CHICAGO, ILLINOIS.

UNCOUPLING DEVICE.

1,079,395.

Specification of Letters Patent. Patented Nov. 25, 1913.

Application filed March 17, 1913. Serial No. 754,731.

To all whom it may concern:

Be it known that we, CHARLES A. CARSCADIN and GEORGE A. WOODMAN, citizens of the United States, both residing at Chicago, 5 in the county of Cook and State of Illinois, have jointly invented certain new and useful Improvements in Uncoupling Devices, of which the following is a specification.

Our invention relates in general to un- 10 coupling devices such as are in use upon railway cars and the like, and aims to provide a new and improved means for lifting the locking pin of a coupler of any of the ordinary types.

One of the principal objects of our invention is to provide a car uncoupling device which may be operated from the side of the car and which will be so constructed that the operating rod may be connected directly 15 to the locking pin of the coupler, obviating thereby the use of chains, links and clevises which are at present employed in many forms of devices of this character to connect the operating rod to the locking pin of the 20 coupler. The use of uncoupling devices employing these members to connect the operating rod to the locking pin of the coupler has subjected the railway companies to considerable annoyance and expense by reason 25 of the theft of these parts, which has thereby rendered the uncoupling device inoperative and required the brakeman to enter between the cars to couple or uncouple them at great 30 risk to himself and in violation of the regulations of the railway commission.

Our invention aims to overcome this and other disadvantages by providing a new and improved uncoupling device wherein all of the parts which can be easily and sur- 0 reputitiously removed will be eliminated, and which at the same time can be readily applied to the car and easily operated.

Further aims and advantages of our invention will be apparent as it is better understood from the following description which, taken in connection with the accompanying drawing, discloses two preferred embodiments thereof.

On the drawing: Figure 1 is a top plan view of a portion of a car and coupler provided with an uncoupling device embodying our invention; Fig. 2 is an enlarged side elevation of a bracket and sliding link which together form the extensible member pro-

vided to connect the operating rod to the car; Fig. 3 is an end elevation of the bracket and link shown in Fig. 2; Fig. 4 is a vertical central sectional view taken through the bracket to more particularly disclose the link; Fig. 5 is a top plan view of the link, and Fig. 6 is a vertical central sectional view of a slightly modified form of bracket.

The invention comprises broadly an operating rod 10, a bracket 11 and an extensible member 12, said bracket and member being fastened to the car and embracing the rod so that the rod may slide transversely of the car.

In the present instance the operating rod is connected directly to the locking pin of the coupler by an arm 13 extending outwardly from the car at right angles to the body portion of the rod and inserted through the eye 14 of the locking pin 15 of the coupler 16. The end of the arm 13 is bent, as shown, at 17 to extend rearwardly of the locking pin so that the operating rod may not be disconnected from the locking pin when the parts are in operative position upon the car. The bracket 11 through which the operating rod is disposed is fastened to the end of the car at 18 adjacent one side, so that the operating arm 19 at the end of the body portion of the rod adjacent the side of the car may be operated without requiring that the brakeman enter between the cars to couple and uncouple them. The bracket 11 is of the ordinary construction except that the aperture 21, through which the operating rod is disposed, is appropriately enlarged to permit the operating rod to move angularly about the bracket, as will be later described.

The extensible member 12 in the present instance comprises a bracket 22 fixed to the car by means of bolts 23 near the junction of the body portion of the rod with the lifting arm 13, and a slide or link 24 slidably mounted in the bracket 22 to move longitudinally substantially in a horizontal plane toward and from the car. The body portion of the operating rod is disposed through the link 24 so that the link and bracket 22 together form means for slidably securing the inner end of the rod to the car body and together these elements constitute an extensible member which restrains the movement of the rod to a horizontal plane about a pivotal

center in the bracket 21. The bracket 22, as shown in Figs. 2, 3 and 4 comprises a back plate 25, from which two parallel integral arms 26 extend outwardly. The opposed faces of these arms are arcuately curved transversely to provide the guiding recesses 27, the outer ends of which are closed by shoulders 28. The link 24 in the present instance is rectangular in cross section, as will be seen by comparing Figs. 2 and 5, and is of appropriate height to fit loosely between the two shoulders 28 of the arms 26. Two oppositely disposed outwardly extending lugs 29 are provided at the inner end of the link to loosely fit within the recesses 27 in position to engage the shoulders 28 and prevent the link from being pulled out of the bracket 22. The arms 26 and the link 24 are given sufficient length to permit movement of the operating rod toward and from the car end an amount greater than the maximum range of travel of the locking pin lengthwise of the car. Upon opposite sides of the link near the lugs 29 are provided recesses 31 which permit the link to be inserted within the bracket 22 when the uncoupling device is assembled. The distance between the inner edges of these recesses is such that the link may be turned about its longitudinal axis when the recesses 31 align with the shoulders 28 to bring the lugs 29 into and out of the recesses 27. To assemble the device, the link is inserted between the arms 26 with the lugs disposed substantially in a horizontal plane until the recesses 31 align with the shoulders 28. The link is then given a quarter turn about its longitudinal axis into operative position to dispose the lugs 29 behind the shoulders 28.

It will be apparent as the recesses 31 are located at the inner end of the link and the shoulders 28 at the outer ends of the arms that the recesses and shoulders can only align when the link and bracket are in extreme extended relation. This position is rarely attained in service and never when the cars are at rest, so that when the operating rod is disposed through the link, and the link 24 and bracket 22 operatively positioned on the car, they can not be disconnected without removing either the locking pin from the coupler or the bracket 22 from the car. The preferable normal relative relation between the operating rod, and the link and bracket 22 is shown in Fig. 2 in which the rod is disposed just inwardly of the ends of the arms 26. When the parts are constructed to provide this relation it will be apparent that the operating rod may move inwardly of the car until it forces the rear end of the link in contact with the back plate 25 of the bracket and may move outwardly from the car and beyond the ends of the arms 26 until the lugs 29 of the link engage the shoulders 28 of the arms. But, as has

been stated, the link and arms are given sufficient length to prevent the operating rod from moving the link throughout its maximum travel. When the parts are operatively connected, the operating rod prevents the turning of the link, even should the recesses 31 be alined with the shoulders 28, throughout a sufficient angle to permit the lugs 29 to clear the side edges of the recesses 27 in the arms.

In Fig. 6 a slightly modified form 32 of bracket is provided. In this bracket the link is adapted to be inserted through a suitable opening 33 in the back plate 25. This arrangement, of course, obviates the necessity of providing the recesses 31 in the link. When the bracket is constructed in this manner the link is inserted endwise through the opening 33 before the bracket is fastened to the car and before the operating rod is threaded through the link. In all other respects the construction and operation of this modified form of bracket member is identical with that of the bracket member 26.

If desired, openings 34 may be provided in the lower arm to permit substances, such as snow, ice, dust and the like, which might collect and prevent the efficient action of the uncoupling device to be swept from between the arms by the movement of the link as the coupler is moved with respect to the car in service.

It is thought that the invention and many of its attendant advantages will be understood from the foregoing without further description and it is obvious that various changes may be made in the arrangement and form of the parts without departing from the spirit or scope of the invention or sacrificing any of its advantages, the forms hereinbefore disclosed being merely preferred embodiments thereof.

We claim:

1. An uncoupling device for railway cars comprising a substantially horizontal operating rod secured to the car and having an end adapted to be connected to the locking pin of the coupler, and means for securing the operating rod to the car, said means comprising a pair of bearing brackets for the operating rod, one of said brackets being provided with a guideway extending transversely of said operating rod and a slide working in said guideway and carrying said operating rod.

2. An uncoupling device for railway cars comprising a substantially horizontal operating rod secured to the car and having a lifting arm adapted to be connected with the locking pin of the coupler, and means for securing the operating rod to the car, said means comprising a pair of bearing brackets for the operating rod, one of said bearing brackets being provided with a guideway

- disposed transversely of the operating rod and a slide working in said guideway and carrying said operating rod, said slide being provided with a longitudinal slot 5 through which said rod extends.
3. An uncoupling device for railway cars comprising an operating rod adapted to be secured to a car and to be connected to the locking pin of the coupler, and means for 10 securing the operating rod to the car comprising a member having a pair of outwardly extending arms and adapted to be fastened to the car, and an element embracing said rod and slidably mounted between 15 said arms to move longitudinally thereof.
4. An uncoupling device for railway cars comprising an operating rod adapted to be secured to a car and be connected to the locking pin of the coupler, and means for 20 securing the operating rod to the car comprising a member for retaining the rod in position and having a pair of outwardly extending arms adapted to be fastened to the car, and a link slidably mounted between 25 said arms to move longitudinally thereof and adapted to embrace the said rod.
5. An uncoupling device for railway cars comprising an operating rod adapted to be secured to a car and be connected to the locking pin of the coupler, and means for 30 securing the operating rod to the car comprising a member having a pair of outwardly-extending arms adapted to be secured to the car between which the said rod 35 is movable horizontally when the parts are in position, and a slidable member for restraining excessive movement of said rod
- outwardly of said arms, said member being mounted to slide between the arms.
6. An uncoupling device for railway cars 40 comprising an operating rod adapted to be secured to a car and be connected to the locking pin of the coupler, and means for securing the operating rod to the car comprising a member having a pair of outwardly extending arms provided with opposed longitudinally disposed recesses, a link slidably mounted between the arms and adapted to embrace said rod, and means carried by the link loosely and slidably disposed in said recesses for engaging the end walls of the recesses to prevent removal of the link, without removing said member from the car or the locking pin from the 45 coupler.
7. An uncoupling device for railway cars comprising an operating rod adapted to be secured to a car and be connected to the locking pin of the coupler, and means for 50 securing the operating rod to the car comprising a member having a pair of outwardly disposed arms, a link mounted to slide freely longitudinally of and between said arms and adapted to embrace the said rod, adjacent faces of the said arms and link being formed to prevent removal of the link, without removing said member from the car or the locking pin from the 55 coupler.
